UNITED STATES PATENT OFFICE.

DANIEL W. HOGE, OF CHICAGO, ILLINOIS, ASSIGNOR TO BASH OIL AND REFINING COMPANY, OF CHICAGO, ILLINOIS, A CORPORATION OF DELAWARE.

METHOD OF TREATING PETROLEUM VAPOR.

Application filed May 25, 1918, Serial No. 236,449. Renewed August 21, 1923.

To all whom it may concern:

Be it known that I, DANIEL W. HOGE, a citizen of the United States, residing at Chicago, in the county of Cook and State of Illinois, have invented certain new and useful Improvements in Methods of Treating Petroleum Vapor, of which the following is a specification.

This invention relates to a method of 10 treating petroleum vapor to break down the high boiling point compounds into low boiling point compounds having the characteristics of those present in commercial gasoline.

15 Large quantities of the heavier fractions of petroleum are available because the demand therefor cannot be stimulated beyond a certain point which leaves a considerable residue in the hands of the refiners who are 20 accordingly anxious to find any means of utilizing these by-products. I have discovered a method of and apparatus for treating petroleum and the heavier fractions thereof whereby this material is converted 25 into low boiling point compounds which may be utilized as commercial gasoline in internal combustion engines and for other purposes to which commercial gasoline is adapted.

30 It is the object therefore of my invention to provide a method of operating whereby the vapors of petroleum and the heavier fractions thereof are readily and cheaply converted into materials analogous to and serving the purpose of gasoline.

35 Further objects and advantages of my invention will be apparent as it is better understood by reference to the following specification when read in connection with the accompanying drawing illustrating the preferred embodiment thereof, in which

Figure 1 is a diagrammatical illustration of an apparatus adapted for use in carrying out my method;

40 Figure 2 is a longitudinal section through the apparatus in which the vapors are treated; and

45 Figure 3 is a transverse section through the same apparatus.

50 Figure 1 is intended merely to diagrammatically illustrate the apparatus so that the purpose and function of my invention may be clearly understood. In this figure, 5 illustrates a suitable still in which the petroleum or heavier fractions thereof is

volatileized and 6 illustrates a condenser where the final products are received. The apparatus 7 in which the vapors are treated is supported in a suitable furnace 8 heated by means of a burner 9 and is connected by 60 a pipe to the header 11 which is in turn connected by a pipe 12 to the still 5. A pipe 13 conveys the product of the method from the apparatus 7 to the condenser 6.

The apparatus for treating the vapor comprises a deep, narrow kettle 14 preferably constructed of cast metal and adapted to hold a bath of molten lead or other suitable metal or heat interchanging material. Within this bath is a tortuous conductor for vapor preferably cast integral and comprising U shaped conducting pipes 15 connected at their upper ends to a header 16 provided with partitions 17 arranged so that the vapor passes through each of the U pipes 15 70 in succession. These partitions form small end chambers 19 and double intermediate chambers 20 with which the pipes are connected. Threaded plugs 18 in the top of the header 16 permit access to the interior 75 of the pipes 15 to remove obstructions which may occur therein. One or more kettles 14 are mounted in the furnace 8 which is provided with one or more burners 9 whereby the desired temperature is maintained. The 80 lead is thus held in a molten condition at a uniform temperature which may be varied and regulated at will.

In carrying out my invention the vapor from the still 5 is delivered to the apparatus 90 7 under a pressure sufficient to maintain a predetermined rate of flow but without relation to the maintenance of any degree of temperature. In normal operation the velocity of the vapor is substantially 62 $\frac{1}{2}$ cubic 95 feet per minute under pressure of 16 ounces per square inch above normal atmospheric pressure. The temperature of the lead bath ranges from the melting point of lead to the destructive point of a cast iron pan and depends upon the character of the vapor being treated. The coil may be made with a header 29" long by 3 $\frac{1}{4}$ " wide by 3 $\frac{1}{4}$ " high with 2" pipes mounted therein on 3 $\frac{1}{4}$ " centers. At each end of the header there is a 100 small chamber 19 approximately 2 $\frac{1}{2}$ " wide by 2 $\frac{1}{4}$ " high by 2 $\frac{1}{4}$ " long and three intermediate chambers each 2 $\frac{1}{2}$ " wide by 2 $\frac{1}{4}$ " high by 7 $\frac{1}{8}$ " long. The kettle is of sufficient 105 size to receive the coil and submerge it in a 110

bath of lead. I prefer that the lead level shall be approximately at the top of the header. In treating gas oil and fuel distillate a temperature ranging from 850° F. at the beginning of the run to a maximum of 1200° F. at the end of the run has been used. It will be distinctly understood, however, that I do not restrict myself to the foregoing specific details with regard to my invention as the same are given merely for the purpose of making the invention clearly understood and not to limit its scope.

The temperature of the vapor varies according to the quality of the vapor being treated and may range from 650° F. to 1100° F.

It will be noted that the cross sectional area of the pipes 15 is relatively slight as compared to the total length of the combined pipes. This permits substantially all of the vapor to contact directly with the walls of the pipes during the passage of the vapor at substantially the velocity above noted. I have discovered, however, that it is essential to break up the flowing stream of vapor at intervals during its passage through the apparatus in order to insure that all of the vapor contacts with the heated walls of the pipes. In the apparatus illustrated and described it will be noted that vapor issuing from the upper end of the second leg of each of the pipes 15 impinges directly and with considerable force against the top of the header 16. Thus the vapor is thoroughly mixed and deflected into the first leg of each of the pipes 15 and during the progress of the vapor through the apparatus every molecule of high boiling point compound in the vapor contacts with the highly heated walls of the pipes 15 and is through the action of the heat disrupted or broken down into low boiling point compounds having the characteristics of commercial gasoline.

This result is accomplished in the apparatus while under substantially no pressure so that the method may be carried out with perfect safety and under conditions insuring the highest efficiency.

The claims of the present application are directed to the action on the vapor which takes place at the upper end of the second leg of each of the substantially U-shaped pipes, as distinguished from the action on the vapor which takes place at the abrupt bends at the lower ends of the pipes, which latter action constitutes the subject matter of the claims of my co-pending application, Ser. No. 105,584, filed June 24, 1916.

I claim:

1. A method of treating vapor of petroleum or the heavier fractions thereof which comprises, conducting the vapor under a

pressure sufficient only to cause it to advance through a reaction zone of relatively great length and small cross sectional area, maintaining said vapor during its passage through said reaction zone at a substantially uniform temperature sufficient to break down compounds having high boiling points into compounds having relatively low boiling points, subjecting the stream of vapor during its movement through said reaction zone to successive abrupt impingements, and permitting the vapor to flow unobstructedly through the reaction zone portions lying between the successive points of impingement.

2. A method of treating vapor of petroleum or the heavier fractions thereof which comprises, conducting the vapor under a pressure sufficient only to cause the vapor to advance through a reaction zone of relatively great length and small cross sectional area, maintaining the vapor during its passage through said reaction zone at a substantially uniform temperature between 650° F. and 1100° F. sufficient to break down compounds having high boiling points into compounds having relatively low boiling points, subjecting the stream of vapor during its movement through said reaction zone to successive abrupt impingements, and permitting the vapor to flow unobstructedly through the reaction zone portions lying between the successive points of impingement.

3. A method of treating petroleum or the heavier fractions thereof to produce a condensate containing low boiling point compounds having the characteristics of those present in commercial gasoline which comprises, subjecting the petroleum or heavier fractions thereof to heat sufficient to convert it into vapor, and subjecting a continuous flowing stream of the vapor, in a separate reaction zone of relatively great length and small cross sectional area and at a pressure sufficient only to cause the stream of vapor to advance through said reaction zone, to a substantially uniform temperature sufficient to break down the compounds having high boiling points into compounds having relatively low boiling points, subjecting the stream of vapor during its movement through said reaction zone to successive abrupt impingements, and permitting the vapor to flow unobstructedly through the reaction zone portions lying between the successive points of impingement.

DANIEL W. HOGE.
